UNITED STATES PATENT OFFICE.

ALEXANDER E. REDLICH, OF CHICAGO, ILLINOIS.

DESIGN FOR A BOTTLE.

43,827.

Specification for Design.

Patented Apr. 8, 1913.

Application filed October 31, 1912. Serial No. 728,907. Term of patent 7 years.

To all whom it may concern:

Be it known that I, ALEXANDER E. REDLICH, a citizen of the United States, residing at Chicago, in the county of Cook and State of Illinois, have invented a new, original, and ornamental Design for Bottles, of which the following is a specification, reference being had to the accompanying drawing, forming part thereof.

I claim:—

The ornamental design for a bottle, as shown.

ALEXANDER E. REDLICH.

Witnesses:

JOHN HOEPPEL, Jr.,
PETER C. SCOT.
